CHARLES B. LOWE, OF DETROIT, MICHIGAN, ASSIGNOR TO FERRO STAMPING & MFG. COMPANY, OF DETROIT, MICHIGAN, A CORPORATION OF MICHIGAN

DOOR-LATCH MECHANISM

Application filed March 11, 1929. Serial No. 346,162.

This invention relates to door latch mechanisms, primarily designed for use in connection with doors of vehicle bodies and the like and consists of certain novel features of construction, combinations and arrangements of parts that will be hereinafter more fully described and particularly pointed out in the appended claims.

In the accompanying drawings,—

10 Figure 1 is a fragmentary side elevation of a door latch mechanism embodying my invention;

15 Figure 2 is a view similar to Figure 1 but showing the bolt retracted from the inner side of the door;

20 Figure 3 is a rear elevation of the construction shown in Figure 1;

Figure 4 is a horizontal sectional view taken on the line 4—4 of Figure 1;

25 Figure 5 is a vertical sectional view taken on the line 5—5 of Figure 1.

Referring now to the drawings, 1 is a case plate adapted to be secured to the inner side of a door having a lateral flange 2 at its forward edge adapted to be secured to the free edge of the door, 3 is a reciprocating latch bolt that is movable through an opening in the lateral flange 2 for engagement with a suitable keeper (not shown). 4 is a latch bolt shank rigidly secured to and constituting a rearward extension of said bolt 3, and 5 is a helical spring anchored on the case plate and having an arm 6 engaging a lateral flange 7 of the shank and normally retaining the bolt 3 in projected position.

35 In the present instance the shank 4 is adapted to slide over but is spaced from the case plate 1. Preferably, a portion 8 of the case plate is pressed out and serves as a bearing for the shank at the rear end thereof and carries a stud 9 that is received in an elongated slot 10 in the shank and guides the same in its sliding movements. Intermediate of its ends the shank 4 is provided with an upwardly opening slot 11 having an upwardly and rearwardly inclined edge 12 that is engaged by a roller 13 on a pin 14 projecting laterally from a reciprocating actuator 15 on the case plate 1. As shown this actuator 15 is slidable between the case plate 1

and shank 4 in a plane at substantially right angles to the shank and is guided in its movements by suitable studs 16 and 17 respectively. Preferably, the stud 16 projects laterally from the case plate 1 and is received in an elongated slot 18 in the actuator while the stud 17 projects laterally from the actuator and travels in a keyhole slot 20 in the case plate 1.

For retracting the bolt 3 I have provided a roll back 21 that is adapted to be spaced from the outer side of the door, and a rotatable rod 22 that is adapted to be operated from the inner side of the door. As shown, the roll back 21 has a hub 23 journaled in the case plate 1 adjacent to the lateral flange 2 and has a lateral arm 24 that is engageable with a lateral arm 25 of the actuator at the upper end thereof to effect a retraction of the bolt 3 while the rod 22 is journaled in brackets 26 and 27 on the case plate below the shank 4 and in substantially parallel relation thereto and is provided intermediate the brackets 26 and 27 with a crank portion 28 that is engageable with upwardly and outwardly inclined inner edges 29 and 30 respectively of the laterally spaced lugs 31 and 32 on the actuator 15 at the lower end thereof to effect a retraction of the bolt.

Due to the constant engagement between the roller 13 on the actuator and the inclined edge 12 of the shank and the engagement of the spring arm 6 with the lateral flange 7 of the shank, the said spring 5 not only serves to normally hold the bolt 3 in projected position but also serves through the cam engagement of the inclined edge 12 with the roller 13 to normally hold the actuator 15 in raised position with the lateral arm 25 thereof against the roll back arm 24. In fact, the pressure of the spring 5 exerted through the parts just mentioned to the roll back 21 causes the said roll back to be normally held in upright position against the lateral flange 2 of the case plate and thereby insures the outside operating handle (not shown) for the roll back to be normally held in a proper predetermined position.

Any suitable means such as the coil spring 33 may be used to normally hold the rod 22

in operative bolt retracting position. As shown, this spring 33 is sleeved on the rod 22 and has its opposite ends respectively connected to said rod 22 and overlapping the case plate 1. It will also be noted that a ring 34 is non-rotatively secured upon this rod 22 and is received in a slot 35 in the bracket 27 so as to prevent longitudinal movement of the rod 22 relative to the brackets 26 and 27 and of the case plate. Any suitable operating means or handle (not shown) may be used upon the inner side of the door to rotate the rod 22 to effect a retraction of the bolt.

15 Thus, with this construction, the bolt 3 may be retracted from the outer side of the door by rotating the roll back 21 clockwise to cause the arm 24 thereof to depress the actuator 15 and thereby cause the cam engagement between the roller 13 and inclined edge 12 of the yoke to become active and move the shank and bolt rearwardly against the tension of the spring 5. In this connection it will be noted that when the actuator is pressed down 20 by the roll back 21 the lugs 31 and 32 on the actuator will move downwardly therewith and away from the crank 28 of the rod 22 so that the retraction of the bolt from the outer side of the door will not effect the inner bolt retracting means. Likewise the bolt 3 may be retracted from the inner side of the door by merely rotating the rod 22 to cause the crank 28 thereof to ride upon the inclined edges 29 and 30 of the lugs 31 and 32 and thereby press the actuator 15 downwardly so as to cause the cam engagement between the roller 13 and inclined edge 12 of the shank to become active to move the shank and bolt rearwardly against the tension of the spring 5. Moreover, since the arm 25 of the actuator 15 is moved away from the roll back arm 24 when the actuator is moved by the inside bolt retracting means, the outside bolt retracting means including the roll back 21 will not be effected when the bolt 3 is retracted from the inside. Thus the inside and outside bolt retracting means are independently operable to effect the retraction of the bolt.

50 Any suitable means such as the dog 40 pivoted on the case plate 1 may be actuated by a handle 41 on the inner side of the door to engage a shoulder 42 of the roll back to render the outside bolt retracting means inoperative to retract the bolt.

55 While it is believed that from the foregoing description the nature and advantages of the invention will be readily apparent, I desire to have it understood that I do not limit myself to what is herein shown and described and that such changes may be resorted to when desired as fall within the scope of what is claimed.

60 What I claim as my invention is:

65 1. In a door latch, a latch bolt having a shank, an actuator for the bolt including a

part extending at right angles to and operatively connected to the shank, and a rotary member substantially parallel to the shank having a portion engageable with the part aforesaid to effect a retraction of the bolt.

70 2. In a door latch, a latch bolt having a shank provided with a cam surface, an actuator extending across said shank, a part carried by said actuator engageable with said cam surface to actuate said shank, and actuating means for said actuator including a movable member substantially parallel to the shank and having a portion engageable with the actuator.

75 3. In a door latch, a latch bolt having a horizontally disposed shank, and actuating means for the bolt including an actuator crossing the shank and movable longitudinally in substantially a vertical plane, a part carried by the actuator engageable with the shank, projections upon the actuator above and below the shank, and independently operable members respectively engageable with said projections.

80 4. In a door latch, a movable latch bolt shank, a member crossing the shank and operatively connected thereto to actuate the same, a member substantially parallel to the shank and operatively connected to the last mentioned member to actuate the same, and means for detachably maintaining the operative connection between said members including a yieldable element engaging the shank.

85 5. In a door latch, a latch bolt having a horizontally disposed shank, and independently operable means for actuating said bolt including two members respectively above and below the shank, one of said members being substantially parallel to the shank, and vertically slidable means common to both members and operatively associated with said shank.

90 6. In a door latch, a latch bolt having a horizontally disposed shank, a vertically disposed actuator for the shank, and independently operable members respectively above and below the shank and moving said actuator.

95 7. In a door latch, a latch bolt having a horizontally disposed shank, and actuating means for the bolt including a vertically movable actuator crossing and operatively connected to the shank, a member engageable with the actuator at one end thereof, and an independently operable member crossing and engageable with the actuator at the other end thereof.

100 8. In a door latch, a latch bolt having a sliding shank, and actuating means for said bolt including two independently operable pivotally mounted members located respectively above and below said shank, a reciprocating member crossing said shank and actuatable by said pivotally mounted members, and

a part projecting from the reciprocating member and engageable with said shank.

9. In a door latch, a latch bolt having a sliding shank, and actuating means for said bolt including two independently operable members located respectively above and below said shank, a sliding member crossing said shank and actuatable by said independently operable members, and an element carried by said slideable member and engageable with said shank.

In testimony whereof I affix my signature.
CHARLES B. LOWE.
